UNITED STATES PATENT OFFICE.

SAMUEL V. KENNEDY AND CHARLES S. SHARP, OF AUBURN, NEW YORK,
ASSIGNORS TO D. M. OSBORNE AND COMPANY, OF AUBURN, NEW YORK,
A CORPORATION OF NEW YORK.

GRAIN-DIVIDER FOR HARVESTERS.

SPECIFICATION forming part of Letters Patent No. 780,744, dated May 24, 1904.

Application filed December 1, 1903. Serial No. 183,314. (No model.)

To all whom it may concern:

Be it known that we, SAMUEL V. KENNEDY and CHARLES S. SHARP, citizens of the United States, residing at Auburn, in the county of Cayuga and State of New York, have invented certain new and useful Improvements in Grain-Dividers for Harvesters, of which the following is a full, clear, and exact description.

Referring to the drawings, Figure 1 is an elevation of the grain-wheel end of a harvester, showing the divider in position. Fig. 2 is a plan of the same, showing the divider dismounted and resting on the platform. Fig. 3 is a detail section on line xx , Fig. 1. Fig. 4 is a section on line yy of the same figure, and Fig. 5 is a detail of the same parts from the same point of view.

In the drawings, A is the finger-bar, secured to the harvester-platform. A casting B is rigidly fastened to the finger-bar and sustains the front end of a brace C, which extends to the rear of the platform and forms a partial support for the grain-wheel mechanism.

D is a casting forming the point of the divider and to which the divider-board A' is bolted.

E is a supporting-bar for the divider. Its rear end is pivoted to the casting B by a vertical pivot b' . To its front end is pivotally connected a small casting c' by a horizontal pivot a . The small casting c' is also pivotally connected to the divider-point D by a vertical pivot b . A socket a' is formed in the casting B, in which rests an end of a post F, bolted to the divider-board.

Integral with the outer finger on the finger-bar and secured to the latter is a bracket G, having thereon a lock H, which engages with the bar E and retains it securely in position.

The lock H comprises a casing I, bolted to the bracket G, inclosing a bolt or plunger c , which is held down in a locked position by a coiled spring d , which surrounds the bolt, one end of said spring engaging with a pin e in the bolt and the other end with the inner top of the casing. A button is provided on the top

of the bolt c to raise it out of engagement with the bar E.

When it is necessary to narrow the width of the harvester for purposes of transportation on a road or through a gateway or for storage purposes, first raise the bolt c out of engagement with the hole c' in the bar E. Then lift the inner end of the divider-board A', which moves on its horizontal pivot a , until the post F is clear of the socket a' in the casting B. The bar E is then swung on its pivot in toward the platform and nearly parallel with the finger-bar, the divider-board moving inward and along the platform by reason of its vertical pivot b . When the farthest movement of the bar E has been reached, the divider-board, moving on the horizontal pivot a , is lowered until it rests on the platform, as clearly shown in Fig. 2.

To restore the divider to an operative position, the divider-board is lifted from the platform and the bar E swung outwardly on its pivot at b until it is in contact with the bolt c . The bolt is then raised and the bar E moved under it until the hole c' is directly beneath the bolt and through which the bolt passes when released. The post F is then inserted in the socket a' . The divider is thus held firmly and securely in its usual operative position, as clearly shown in Fig. 1.

Having thus described our invention, what we claim, and desire to cover by Letters Patent, is—

1. In a harvester, the combination of a finger-bar, a horizontally-swinging supporting-bar connected thereto, a divider pivoted on the supporting-bar to rest upon the harvester-platform when the supporting-bar is substantially parallel with the finger-bar.

2. In a harvester, the combination of a finger-bar, a casting thereon, a supporting-bar hinged to said casting, a lock to hold the supporting-bar, a divider pivoted to the supporting-bar, a post on said divider, and a socket in the casting in which said post rests.

3. In a harvester, the combination of a fin-

ger-bar, a casting thereon, a swinging supporting-bar hinged to said casting, a lock to hold it in position, a divider secured to the supporting-bar by a vertical pivot, a post on the divider, and a socket in the casting in which the post rests.

4. In a harvester, the combination of a finger-bar, a casting thereon, a supporting-bar hinged to said casting, a divider on the supporting-bar, a post on said divider, a socket in the casting in which the post rests, a bracket on the finger-bar and a lock on said bracket to engage the supporting-bar.

5. In a harvester, the combination of a finger-bar, a supporting-bar pivotally connected to the finger-bar, a divider connected to the supporting-bar by horizontal and vertical pivots, a post on the divider, a support for the

post, a bracket on the finger-bar, and a lock on said bracket to engage with the supporting-bar.

6. In a harvester, the combination of a divider comprising a supporting-bar pivoted to fold horizontally inward along the finger-bar, and a divider-board pivotally connected to the outer end of the bar so as to swing over the platform in a position transverse to the finger-bar when the supporting-bar is folded inward.

In testimony whereof we hereunto set our hands, this 19th day of November, 1903, in the presence of two attesting witnesses.

SAMUEL V. KENNEDY.
CHARLES S. SHARP.
